SEWAGE SEPTIC TANK

Holmes E. Boyd, 2506 S. Lakeview Drive,
Sebring, Fla. 33870

Filed Feb. 18, 1971, Ser. No. 116,730

Term of patent 14 years

Int. Cl. D23—01

U.S. Cl. D23—2

FIG. 1

FIG. 2

FIG. 3

FIG. 4

FIG. 1 is a top plan view of a sewage septic tank embodying my new design;

FIG. 2 is a side elevational view;

FIG. 3 is a bottom view; and

FIG. 4 is an end elevational view.

The characteristic feature of my design resides in the specific configuration of the ends of the septic tank as shown.

I claim:

The ornamental design for a sewage septic tank, as shown and described.
